[57] CLAIM

The ornamental design for a thermal shield for parabolic reflector medical examination light, as shown and described.

DESCRIPTION

FIG. 1 is a perspective view of a thermal shield for parabolic reflector medical examination light showing my new design, the light being shown in broken lines for illustrative purposes only;

FIG. 2 is one end elevation view thereof, the opposite end elevation view being identical thereto;

FIG. 3 is one side elevation view thereof, the opposite side elevation view being identical thereto;

FIG. 4 is a top plan view thereof; and,

FIG. 5 is a bottom plan view thereof.

FIG. 3

FIG. 4

FIG. 5
